TELEPHONE SYSTEM

Norman H. Saunders, Chicago, Ill., assignor to
 Associated Electric Laboratories, Inc., Chicago,
 Ill., a corporation of Delaware

Application October 21, 1935, Serial No. 45,845

20 Claims. (Cl. 179—26)

The invention relates in general to telephone systems but more particularly to inter-exchange calls in which an operator is required to complete connections between automatic subscribers' 5 lines over trunk lines connecting two automatic exchanges.

The main object of the invention is the provision of means whereby an automatic subscriber in one exchange in order to call an automatic subscriber in another exchange must first call the toll operator over a toll trunk extending from one of the automatic exchanges to the toll exchange, after which the toll operator dials back over this same trunk to operate the automatic 10 switches to complete the desired connection. When such connection is completed the toll operator may disconnect and free her trunk leaving the connection between the two automatic subscribers established over one of the trunk lines 15 connecting the two automatic exchanges.

One feature of the invention relates to the provision of a monitoring selector operable by the toll operator to monitor the trunks between the two automatic exchanges to determine their idle 20 or busy condition.

Other features relate to the circuit refinements in the dial back repeater which enables this type of service to be given.

The drawings, comprising Figs. 1 to 7, inclusive, show by means of the usual circuit diagrams, a sufficient amount of apparatus to enable the invention to be described and understood.

Fig. 1 shows one of the trunks extending to a distant automatic exchange terminating in an outgoing repeater and an incoming rotary line switch in the local automatic exchange.

Figs. 2 and 3 show the detail circuits of the novel dial-back repeater and Fig. 3 shows one 40 of the trunks extending to the distant toll switching center.

Fig. 4 shows an all-relay monitor selector for monitoring the trunks connecting the two automatic exchanges.

Fig. 5 shows one of the local selector switches.

Fig. 6 shows the dial-back, incoming toll, and the local line switches, the usual associated master switches, and one of the local subscribers' lines.

Fig. 7 shows a one-line diagram of the trunking arrangement in the local automatic exchange and the trunk lines extending to the distant automatic exchange and the toll switching center.

Referring now in detail to the drawings, Fig. 1 55 shows one of the trunks extending to a distant

automatic exchange terminating in an outgoing repeater and an incoming rotary lineswitch. This lineswitch is the well known type of rotary lineswitch which advances its wipers in response to the deenergization of its stepping magnet. These 5 lineswitches have access to a group of dial-back repeaters, one of which is shown in Figs. 2 and 3. The outgoing repeater comprises a repeating coil RC and five relays, two of which are the usual slow-releasing relays as shown by the cross-hatched lower portion. Relay 103 is the well known shunt field electro-polarized relay having an operating winding and a polarizing winding. This relay operates its armature 133 only when the current flow in the operating winding is in 10 opposition to the polarizing winding. The repeaters are accessible from the sixth level of the local selectors, one of which is shown in Fig. 5, and from the monitor selectors, one of which is shown in Fig. 4.

The dial-back repeater shown in Figs. 2 and 3 comprises a group of relays and a rotary stepping switch having access to trunk lines extending to the toll switching center. This stepping switch is similar in construction and operation 20 to the well known rotary lineswitch which steps its wipers on the deenergization of the stepping magnet. A number of the relays are of the usual slow-to-release type as shown by the cross-hatched lower portion and by the copper sleeves 25 over their cores. Relay 206 is a slow-to-operate relay as indicated by the full-black upper portion. Relays 210 and 212 are differential relays and relay 204 is a shunt field electro-polarized relay similar to the shunt field relay 103 in Fig. 1. Relay 202 has a vibrating spring 220 which vibrates upon operation of armature 221 due to the weight 30 219 on spring 220. The weight 219 may be adjusted so as to vibrate spring 220 for a predetermined time interval after 221 is operated so as 35 to intermittently open and close the circuit to slow-to-operate relay 206. The dial-back repeaters are accessible from the tenth level of the local selectors and from the banks of the incoming rotary lineswitches. Each dial-back repeater has 40 access to an individual dial-back lineswitch, one of which is shown in Fig. 6.

Fig. 4 shows the monitor selector comprising a group of relays, two of which, 403 and 405, are the slow-to-release type as indicated by the 50 sleeves around their cores, and two two-step relays which close only their "x" contacts on their first step and their remaining contacts on their second step when the short circuits around their lower windings are opened. Only two trunk re- 55

lays 401 and 402 are shown, but it will be understood that in case there are more than two trunks to the distant automatic exchange then additional trunk relays are connected in a similar manner. The monitor selector has access to the trunks to the distant automatic exchange by way of the outgoing repeater in Fig. 1 and is accessible from the eighth level of the local selectors.

Fig. 5 shows one of the local selectors which are of the well known Strowger vertical and rotary type of switch. These selectors are of the restricted service type having normal post springs which are operated when the wipers have been raised in a vertical direction opposite the restricted levels. The polarized switching relay 507, as indicated by the bar through its middle, is similar in construction and operation to the relay disclosed in Patent No. 1,673,884, issued June 19, 1928, to H. C. Pye. The local selectors have access to the dial repeaters, the outgoing repeaters, the monitor selector, reverting call switches, and the local connectors as shown in Fig. 7. These selectors are accessible from the dial back, incoming toll, and local lineswitches shown in Fig. 6.

The lineswitches and master switch shown in Fig. 6 are similar in construction and operation to the lineswitch and master switch shown in Patent No. 1,809,086, issued June 9, 1931, to John Voss and B. D. Willis. These lineswitches have access to the local selectors over trunk lines such as trunk line 560, 563. Each local subscriber's line, one of which is indicated by the circle with A in the center, have a local restricted lineswitch individual thereto. Each automatic subscriber, such as A, is equipped with the usual transmitter, receiver, and calling device. The dial-back lineswitches are each individual to and accessible from the dial-back repeaters while the incoming toll lineswitches are each individual to a toll trunk extending to the toll switching center. The dial-back and incoming toll lineswitches are non-restricted, having conductors 680 and 690 for accomplishing a purpose to be more fully described hereinafter.

Referring now to Fig. 7, a general description of the operation will now be given. When a local subscriber such as A calls, the subscriber's local lineswitch plunges and seizes an idle local selector. In case of a local call, subscriber A dials and operates the selector to seize an idle local connector which is thereafter operated to complete the desired local call. In case of a reverting call the calling subscriber dials and operates the selector to select one of the reverting call switches after which the reverting call switches are operated to signal the desired subscriber on his own line when he hangs up. In case a local subscriber attempts to dial the distant automatic exchange direct then the selector is operated to the restricted level where it automatically rotates to the eleventh position where the selector cam springs are operated to give the calling subscriber a busy signal. In order for the local subscriber to be connected to a subscriber in the distant automatic exchange it is necessary for such subscriber to dial the selector to the "O" level to seize an idle dial-back repeater. When the dial-back repeater is seized a splash of generator is transmitted over one of the idle toll trunks to the toll switching center. The toll operator answers and when it is learned that a local subscriber desires connection with a distant automatic subscriber the toll operator unbalances the toll trunk thereby causing the associated dial-

back lineswitch to plunge and select an idle local selector after which the operator dials back over this same trunk to operate the selector to seize an idle outgoing repeater to the distant automatic exchange. The operator now dials the number 5 of the distant automatic subscriber and the outgoing repeater repeats the impulses over the automatic trunk to cause the automatic switches in the distant exchange to complete the desired connection. When the called subscriber answers 10 the toll operator disconnects from the toll trunk, thereby freeing such toll trunk for other calls while the local and distant subscribers talk over the established connection.

Incoming calls from the distant automatic exchange to the local exchange come in over the outgoing repeater causing the incoming rotary lineswitch to select an idle dial-back repeater which then automatically selects an idle toll trunk and signals the toll operator thereover. In order 20 to extend the call to a local subscriber the toll operator unbalances the line thereby causing the associated dial-back lineswitch to seize an idle local selector after which the toll operator dials back over this same toll trunk to operate the local 25 selector and connector to complete the call. When the local subscriber answers the toll operator disconnects and frees her toll trunk for use on other calls.

Since the toll operator is disconnected from the 30 established connections between the local and distant automatic subscribers, a monitor selector is provided in the local exchange to enable the toll operator to determine the busy or idle condition 35 of the trunks connecting the local and distant automatic exchanges. In order to monitor these trunks the toll operator seizes an idle toll trunk thereby causing the incoming toll lineswitch to select an idle local selector after which the local selector is operated to seize the monitoring selector. The toll operator now operates the monitor selector to engage with successive automatic trunks to determine their busy or idle condition.

Having given a general description of the operation, a detailed description will now be given. 45 For this purpose it will be assumed that a local subscriber, such as subscriber A in Fig. 6, desires to call another automatic subscriber in the local automatic exchange. In response to subscriber A removing his receiver a bridge is closed across 50 conductors 670 and 671 thereby completing a circuit for the slow-to-operate line relay 640 as follows: from ground by way of springs 644, conductor 671, through the substation loop, conductor 670, springs 643, and through the winding 55 of relay 640 to battery. At armature 641 line relay 640 at its back contact opens the circuit to the B. C. O. upper winding of relay 646 and at its make contact grounds conductor 672 to make this line busy to the local connectors. At armature 642 relay 640 completes the circuit through the lower pull-down winding of the plunger coil 646 in case no other line relay in this particular group is in operated position. This circuit may be traced as follows: from grounded conductor 660 65 extending from the master switch through the normally closed springs controlled by armatures 612 and 622, front contact and armature 642 and through the lower pull-down winding of plunger coil 646 to battery. In response to the operation 70 of the pull down winding, the plunger (not shown) of the lineswitch plunges into the lineswitch bank to close springs 651, 654, 652, and 653. The pull-down winding of coil 646 also operates its armatures to open the circuit to line 75

relay 640 at springs 643 and 644 and at springs 645 completes a temporary circuit through the upper B. C. O. winding of coil 646 as follows: from ground by way of front contact and armature 641, contact 646, and through the upper B. C. O. winding of coil 646 to battery. Since the master switch maintains the plungers of all idle lineswitches opposite an idle trunk terminating in an idle local selector, as described in Patent No. 1,809,086, the closure of springs 651 and 654 extends the loop including the calling subscriber's line over conductors 560 and 563 and through armatures 526 and 530 and their back contacts to the upper winding of line relay 506 to battery and through the lower winding of line relay 506 to ground at the normally closed contacts controlled by armature 516.

Line relay 506 immediately energizes over the above traced circuit and at armature 524 completes the energizing circuit for release relay 505 as follows: from ground by way of armature 521, armature 524 and front contact, and through the winding of release relay 505 to battery. At armature 525 line relay 506 also prepares the circuit through the upper winding of polarized switching relay 507. Release relay 505, upon energizing, at armature 520 grounds conductor 561 by way of the busy key 523 to maintain the local lineswitch operated and the calling line busy to local connectors after the line relay 640 in the plunger lineswitch restores. At armature 522 release relay 505 completes the circuit through the lower polarizing winding of switching relay 507 and completes an energizing circuit through the lower winding of series relay 504 by way of off normal springs 511, and at armature 521 opens a point in the circuit to the release magnet 501 at its back contact and at its front contact prepares a circuit for holding the series relay 504 in energized position during the dialling period and for operating vertical magnet 503.

In the local lineswitch the slow-to-release line relay 640 deenergizes after ground is returned over connector 561 and which ground extends by way of springs 653 and through springs 645 and armature 641 and back contact in parallel to the upper winding of coil 646. At armature 642 the de-energization of line relay 640 again establishes the chain circuit to the master switch.

Series relay 504 energizes over the previously traced circuit through its lower winding, and at armature 516 disconnects ground and substitutes ground through the dial-tone source by way of cam springs 513. At armature 517 relay 504 opens a further point in the circuit to the release magnet, at armature 518 prepares another point in the circuit for maintaining itself in operated position during the dialling period, and at armature 519 opens a point in the circuit through the rotary magnet 503. Dial tone is now transmitted to the calling subscriber by way of dial-tone source, cam springs 513, armature 516 and front contact, through the lower winding of line relay 506, back contact and armature 530, from thence over conductors 563 and 671 through the substation loop back over conductors 670 and 560 and through the upper winding of line relay 506 by way of armature 526.

In response to hearing dial tone the calling subscriber now dials the first digit of the local called subscriber's number. Line relay 506 follows the impulses in the dialled digit and in response to its deenergization at armature 524 and back contact completes a circuit for energizing the vertical magnet 502 and for maintaining series

relay 504 in operated position as follows: from grounded armature 527, armature 524 and back contact, armature 521 and front contact, armature 518, and through the vertical magnet 502 and the upper winding of series relay 504 in multiple to battery. Vertical magnet 502 is energized in response to each impulse to step the wipers 540 to 542 one step in a vertical direction, while series relay 504 due to its slow release characteristics is maintained in operated position over this pulsing circuit during the dialling period. At armature 524 line relay 506 temporarily opens the circuit through the release relay 505 but the release relay being of the slow-to-release type maintains its armature in operated position during the dialling period. On the first vertical step of the wipers off-normal springs 510 prepares a point in the circuit to the release magnet 501, off-normal springs 511 opens the original energizing circuit of series relay 504, and off-normal springs 512 prepares a point in the circuit to the rotary magnet 503.

Line relay 506 is maintained energized after the dialling period and shortly thereafter series relay 504 deenergizes. At armature 516 series relay substitutes direct ground in place of dial tone, at armature 517 prepares a point in the circuit to release magnet 501, and at armature 519 completes the circuit for operating the rotary magnet 503 as follows: from grounded armature 527, armature 524 and front contact, off-normal springs 512, interrupter contacts 515 of magnet 503, back contact and armature 519, and through the winding of rotary magnet 503 to battery. Rotary magnet 503, upon energizing, steps the wipers one step for each energization and at interrupter springs 515 interrupts the circuit to magnet 503. Rotary magnet 503 due to interrupter springs 515 operates in the manner of a buzzer stepping the wipers in a rotary direction until such time as the circuit is completed for the polarized switching relay 507. The local selector is of the type known as the battery searching type, and therefore the polarized switching relay 507 will not energize until the test wiper 541 encounters a bank contact having battery potential thereon, which potential indicates an idle local connector.

As soon as the test wiper 541 encounters an idle local connector having battery potential on its incoming test conductor a circuit may be traced for energizing the polarized switching relay 507 as follows: from ground by way of armature 520, point 532, back contact and spring 531 of the normal post springs, through the upper winding of relay 507, armature 525, test wiper 541, and engaged bank contact, and over the incoming test conductor of the idle local connector to negative battery. Since the lower electro-polarizing winding of switching relay 507 was energized by way of grounded armature 522 of release relay 505 and since the flow of current through its upper winding is in the proper direction polarized relay 507 now energizes and at armature 527 opens the circuit extending to the rotary magnet 503 to stop the wipers of the selector in engagement with the bank contacts terminating this local connector. At armatures 526 and 530 switching relay 507 switches the calling loop from the windings of the line relay 506 to the windings of the line relay in the local connector.

The line and release relays in the local connector energize in the well known manner and connect ground back over the incoming test conductor, test wiper 541, armature 529, point 532, 75

armature 528, and through the lower winding of polarized switching relay 501 for maintaining this relay in energized position through its lower winding alone as long as ground is maintained 5 on test wiper 541. This same ground transmitted back from the local connector also extends from point 532 by way of the busy key 523 and conductor 561 for maintaining the plunger line switch in operated position and for maintaining 10 the calling line busy to the local connector. Line relay 506 deenergizes in response to the operation of polarized relay 507, and at armature 524 prepares a further point in the circuit to release magnet 501 at its back contacts, and at its front contacts 15 opens the circuit to release relay 505. Slow-to-release relay 505 at armatures 520 and 522 disconnects ground from conductors 561 and the lower winding of relay 507 only after ground has been returned from the seized connector. At 20 armature 521 and back contact release relay 505 prepares another point in the circuit to release magnet 501.

The local connector is operated in the well-known manner by the calling subscriber to complete the desired local connection, the talking circuit including the heavy talking conductors.

In case the local subscriber operates the local selector opposite one of the restricted levels then the normal post springs operate to switch the circuit for operating the polarized switching relay over the restricted service conductor 562 which in this case is not connected in the local lineswitch because the subscribers, such as subscriber A, are restricted from completing calls on the 35 restricted levels. Assuming now that subscriber A has operated the local selector opposite a restricted level and since no circuit is completed for switching relay 507 the rotary magnet 503 continues to operate until the wipers of the selector are rotated to their eleventh position of the bank contacts at which time cam springs 513 and 514 operate. The operation of cam springs 514 completes a circuit through the lower winding of series relay 504 by way of front contact and 40 armature 524 and grounded armature 527. At armature 519 series relay 504 upon energizing opens the circuit to rotary magnet 503 and at armature 516 connects the busy tone to the calling subscriber as follows: from busy tone source 50 by way of the front contacts and cam springs 513, armature 516 and front contact, through the lower winding of line relay 506 and from thence over the calling subscriber's loop, as previously 55 described.

55 In response to busy tone the calling subscriber will replace his receiver, thereupon opening the circuit of line relay 506 whereupon the latter relay deenergizes. At armature 524 line relay 506 opens the circuit to release relay 505 at its 60 front contact and at its back contact prepares a point in the circuit to the release magnet, and at its front contact also opens the circuit through the lower winding of series relay 506, whereupon the latter relay deenergizes. When slow-to-release relays 504 and 505 deenergize, a circuit for operating release magnet 501 may be traced as follows: from grounded armature 527, armature 524 and back contact, armature 521 and back contact, armature 517, off-normal springs 65 510, and through the winding of release magnet 501 to battery. By the operation of the release magnet 501, the wipers 540 to 542 inclusive, are returned to their normal position in the well known manner, and when the wipers reach their 70 normal position the off-normal springs 510 to 512,

inclusive are returned to their normal positions. The cam springs 515 and 514 are also now in normal position. The local selector is released in a similar manner at the completion of a local call over the local connector by the local connector 5 disconnecting ground sent back over the incoming test conductor to test wiper 541 to open the circuit through the lower winding of switching relay 507, whereupon this relay deenergizes. At 10 armature 527 relay 507 completes the circuit for release magnet 501. This ground is likewise disconnected from conductor 561 with the result that the holding circuit through the upper winding of coil 646 of the local lineswitch is opened causing the armatures of this coil and the plunger 15 to be restored to their normal position. This ground is likewise removed from conductor 672 so that local subscriber A may be called over the local connectors.

It will now be assumed that subscriber A desires 20 to call a subscriber in the distant automatic exchange, and in order to do so subscriber A dials the digit 0 to cause the local selector in the same manner as previously described to be raised opposite the tenth level after which the selector 25 rotates step by step in search of an idle dial-back repeater. Assuming further that the dial-back repeater shown in Figs. 2 and 3 is the first idle dial-back repeater, then the circuit for energizing the polarized switching relay 507 in the local 30 selector may be traced as follows: from ground by way of armature 528, resting contact and spring 531 of the normal post springs, upper operating winding of polarized relay 501, armature 525, wiper 541, conductor 161, through the lower 35 winding of impedance 201, conductor 261, normally closed springs 334 of the busy key, armature 313 and back contact, through the resistance R5 to battery. Polarized switching relay 507 energizes over this circuit and at armatures 526 40 and 530 connects the calling subscriber's loop across the windings of the start and battery feed relay 306. This circuit may be traced as follows: from ground through the upper winding of relay 306, conductor 268, conductor 162, wiper 45 542, front contact and armature 530, conductor 563, contact 654, conductor 671, through the substation loop, conductor 670, contacts 651, conductor 560, armature 526 and front contact, wiper 540, conductor 160, conductor 269, and through 50 the lower winding of relay 306 to battery.

Relay 306 energizes over the calling subscriber's loop and at armature 329 completes a circuit by way of conductor 265, armature 243 and back contact, conductor 264, through the winding of battery reversing relay 301 to battery for energizing 55 relay 301. At armature 330 relay 306 completes the circuit for energizing relays 302 and 304. Relay 304, upon energizing, at armature 321 prepares a point in the circuit for energizing 60 switching relay 305, at armatures 322 and 323 prepares a circuit for connecting interrupted generator and ground to one of the toll switching trunks. Relay 301, upon energizing over the above traced circuit, at armature 310 completes 65 a circuit for starting the ringing machine at its front contact and at its back contact opens the circuit to the all-trunk-busy relay (not shown), and at armatures 311 and 312 prepares a reversing circuit to be explained more fully herein-after. Hold relay 302, upon energizing, at armature 313 disconnects the idle battery potential at its back contacts and at its front contact substitutes ground therefor, thereby connecting ground to the incoming test conductor 161 and test wiper 70 75

541 of the local selector to hold the polarized switching relay 507 in energized position and for maintaining the local lineswitch in operated position and the calling line busy to local connectors.

- 5 At armature 314 hold relay 302 grounds conductor 262 to energize the polarizing winding of polar shunt field relay 204, at armatures 315 and 316 short circuits test relay 303 in case the test wiper 343 is in engagement with a busy called toll trunk, while at armature 316 completes a circuit for operating the marginal stepping magnet 307 in case the toll trunk is busy.

In case the toll trunk engaged by the wipers 340 to 343, inclusive, is busy, ground will be present

- 15 on the test conductor 362 which ground extends by way of wiper 343, normally closed springs controlled by armature 328, armature 320 and back contact, armature 316, normally closed springs controlled by armature 319, conductor 271, armature 245, conductor 270, interrupter springs 332, and through the winding of stepping magnet 307 to battery. A branch of this same circuit extends from ground as previously traced to armature 316 and thence through the winding of test relay 303, armature 315, conductor 273, to grounded armature 222, thereby short circuiting the test relay 303 to prevent its energization when the wiper 343 engages a grounded bank contact. The stepping magnet 307 energizes over the above-traced circuit and positions its pawl preparatory to stepping the wipers of the associated switch. Near the end of its stroke magnet 307 opens the interrupter contacts 332, thereby opening its own circuit. Stepping magnet 307 thereupon deenergizes and steps the wipers one step into engagement with the next toll trunk. In case the second called trunk is busy ground is again encountered by test wiper 343 to maintain the test relay 303 short-circuited and again operates the stepping magnet 307.

When test wiper 343 encounters a bank contact without ground potential indicating an idle toll trunk, a circuit may then be traced for energizing the test relay 303 as follows: from grounded armature 222, conductor 273, armature 315, through

- 45 the winding of test relay 303, normally closed springs controlled by armature 319, conductor 271, armature 245, conductor 270, interrupter springs 332, and through the winding of marginal stepping relay 307 to battery. Stepping relay 307 is marginal and will not energize due to the high resistance of relay 303. Relay 303, upon energizing, at armature 317 prepares a circuit through the lower winding of switching relay 305, at armature 319 connects the ring-back circuit to the calling subscriber, at armature 319 substitutes the battery through resistance R7 for the battery through the stepping magnet 307, at armature 320 grounds test wiper 343 and conductor 362, to make 50 this trunk line busy to other dial-back repeaters. Test relay 303 is now locked in energized position over the following circuit: from grounded armature 222, conductor 273, armature 315, through the winding of test relay 303, and through the 55 make contact and armature 319 and resistance R7 to battery.

The ring-back circuit for transmitting ring-back tone to the calling subscriber may be traced as follows: from interrupted generator through

- 70 the multiplied contacts and wiper 340, ring-back condenser, armature 318, conductor 263, armature 215, normally closed contacts controlled by armature 216, conductor 160, from thence over the heavy talking conductors and the calling loop, 75 as previously described.

The circuit for energizing the high resistance winding relay 371 of the delayed ground relay group may be traced as follows: from ground by way of the high resistance winding of relay 371, over common conductor 370, armature 321, front contact and armature 317, through the lower winding of switching relay 305, through the interrupter springs 332, and through the winding of stepping magnet 307 to battery. Due to the high resistance winding of relay 371, switching relay 305 and stepping magnet 307 do not energize over this circuit. Relay 371, however, energizes and at armature 372 completes a circuit for energizing the A. C. relay 376 in case the ringing machine has been started and generator is applied to the 15 generator lead. When A. C. relay 376 energizes it operates armature 375 to close a circuit to the slow-to-operate relay 374. After an interval of time slow-to-operate relay 374 operates its armature 373 to connect direct ground to common conductor 370 to operate the switching relay 305 and to short circuit the high resistance relay 371.

The circuit for energizing switching relay 305 may now be traced as follows: from grounded armature 373, common conductor 370, armature 25 321, front contact and armature 317, lower winding of switching relay 305, interrupter springs 332, and through the winding of stepping magnet 307 to battery. Motor magnet 307 does not energize in series with switching relay 305 but the latter 30 relay at armature 325 completes its holding circuit independent of ground on the delayed-ground lead 370. At armatures 326 and 331 switching relay 305 connects generator out over the toll trunk to signal the toll operator at the 35 toll switching center as follows: from grounded generator through the resistance R6, front contact and armature 322, armature 326, wiper 341, conductor 360, to the toll center, through the signalling apparatus thereat back over conductor 40 361, wiper 342, armature 331, and armature 323 and front contact, to ground. At armature 327 switching relay 305 opens the circuit to the slow-releasing ring-relay 304, and at armature 328 connects direct ground to test wiper 343 to maintain 45 this toll trunk busy. Ringing relay 304 de-energizes after an interval and at armature 321 opens the original energizing circuit of switching relay 305, and at armature 322 and 323 disconnects ringing current at the front contacts and at the back contacts thereof connects the line and 50 differential relays 209 in bridge of the toll trunk. From the foregoing, it will be seen that ringing current has been applied to the toll trunk conductors 360 and 361 for an interval in order to 55 operate the signal at the operator's switchboard.

When the toll operator observes the signal and answers the circuit is completed for energizing line relay 209 as follows: from ground through the lower winding of line relay 209, lower winding 60 of differential relay 210, conductor 267, armature 311 and front contact, resting contact and armature 322, armature 326, wiper 341, conductor 360, over the bridge at the toll board back over conductor 361, wiper 342, armature 331, armature 65 323 and back contact, front contact and armature 312, conductor 266, upper winding of differential relay 210, and through the upper winding of relay 209 to battery. Differential relay 210 does not energize over the above-traced circuit because both windings are equal and oppose each other, but line relay 209 at armature 239 completes an obvious circuit for energizing release relay 208. At armature 240 line relay 209 prepares a point in the loop and impulsing circuit 70 75

extending to the dial-back switches. Release relay 208, upon energizing, prepares a point in the circuit to series relay 205 at armature 235, at armature 236 grounds conductor 261 and the incoming test conductor 161 through the lower windings of impedance 207 to maintain the local switches in operated position, at armature 237 completes a circuit through the lower winding of line reversing relay 201 as well as preparing the locking circuit for tone relay 206, and at armature 238 grounds conductor 274 to maintain the test relay 303 in operated position. Line reversing relay 201, upon energizing, at armature 213 completes the circuit for energizing timing relay 202 at its front contact and at its back contact disconnects ground from the ringing machine start conductor. At armature 214 relay 201 connects another ground circuit through the polarizing winding of the shunt field relay 204 from armature 236, at armature 215 opens the ring-back circuit to the calling subscriber, at armature 217 opens the short circuit around the upper winding of impedance 207 to permit pay-station tone if connected to conductor 161 to be induced from the lower winding of impedance 207 to the upper winding of impedance 207 in order to inform the toll operator that a paystation is calling, and at armatures 216 and 218 reverses battery back over conductors 160 and 162 for supervisory or metering purposes to the calling line. Timing relay 202, upon energizing, operates its armature 221 to start the weight on spring 220 vibrating to intermittently close a circuit to slow-to-operate relay 206. Relay 206 is a slow-to-operate relay and does not immediately operate its armature and therefore does not operate until the vibrations of weighted spring 200 decrease in amplitude or remain closed for an interval of time sufficient for the slow-to-operate relay 206 to operate its armature. After an interval slow-to-operate relay 206 energizes and at armature 233 again short circuits the upper winding of impedance 207 to cut off the pay-station tone if connected to conductor 161 and at armature 234 completes a locking circuit for itself from grounded armature 237.

The talking circuit between the local calling subscriber and the toll operator extends over the heavy talking conductors as follows: conductors 670 and 671, line-switch contacts 651 and 654, conductors 560 and 563, armatures 526 and 530 and their front contacts, wipers 540 and 542, conductors 160 and 162, armatures 218 and 216 and their front contacts, armatures 231 and 230 and their back contacts, condensers C2 and C3, conductors 261 and 266, armatures 311 and 312 and their front contacts, back contacts and armatures 322 and 323, armatures 326 and 331, wipers 341 and 342, and by way of the toll trunk conductors 360 and 361 to the toll operator. Talking battery for the toll operator is furnished through the windings of line relay 209, while talking battery for the local calling subscriber is furnished through the windings of the battery feed relay 306.

When the toll operator receives the information she may extend the call to a distant office, or may call back through the exchange in which the dial-back repeater is located by momentarily unbalancing the toll trunk. It will first be assumed that the toll operator completes the desired call to a distant office and after conversation is terminated and when the calling subscriber hangs up the battery feed relay 306 deenergizes 75 and opens the circuit of reversing relay 301 at

armature 329 and at armature 330 opens the circuit of hold relay 302. Reversing relay 301, upon deenergizing, at armatures 311 and 312 reverses battery back over the toll trunk to give the operator release supervision. Hold relay 302, upon deenergizing, at armature 313 disconnects one of the multiple grounds from the test lead 161, at armature 314 disconnects one of the multiple grounds to the polarizing winding of shunt field relay 204 and at armature 315 disconnects grounded armature 222 from the lower terminal of test relay 303.

When the toll operator disconnects, the circuit to relays 209 and 210 are opened whereupon relay 209 deenergizes. At armature 239 relay 209 opens the circuit to release relay 208 and momentarily operates the series relay 205 which is without effect at this time. Release relay 208, upon deenergizing, at armature 235 opens the momentarily closed circuit to series relay 205, armature 236 disconnects ground from test conductor 161 to free the local switches and disconnect ground from the polarizing winding of the shunt field relay 204, at armature 237 opens the circuit of line reversing relay 201 and unlocks relay 206, and at armature 238 opens the circuit of test relay 303. Line reversing relay 201, upon deenergizing, at armature 217 short circuits the upper winding of impedance 207, at armature 213 opens the circuit of timing relay 202 and again grounds the all-trunk-busy lead, and at armatures 216 and 218 restores the normal line connections. Timing relay 202 deenergizes and at armature 221 opens the circuit to tone relay 206 and tone relay 206, upon deenergizing at armature 233, opens the shunt across the upper winding of the impedance 207. Test relay 303, upon deenergizing, at armature 317 closes a short circuit around the lower winding of switching relay 305 and likewise completes a circuit for energizing stepping magnet 307 as follows: from grounded armature 325, armature 317 and back contact, and through the winding of stepping magnet 307, to battery. Stepping magnet 307, upon energizing, positions its pawls preparatory to stepping the wiper of the switch, and at interrupter springs 332 opens the circuit of switching relay 305. Switching relay 305, upon deenergizing, at armature 325 opens the circuit to stepping magnet 307, at armatures 326 and 331 opens the circuit to the toll trunk, at armature 328 disconnects ground from wiper 343 to free the toll trunk, and at armature 327 prepares a circuit to ringing relay 304. Stepping magnet 307 deenergizes and steps the wipers 340 to 343, inclusive, one step and closes its interrupter springs 332, thereby again establishing the short circuit around the lower winding of switching relay 305. The local switches, such as the local lineswitch and the local selector, release in the same manner as previously described and all of the relays in the dial-back repeater are now in normal position and can now be used on subsequent calls.

Assuming now that at the time the local subscriber seizes a dial-back repeater, all of the toll trunks are busy. In this case, all of the conductors, such as conductor 362 individual to each toll trunk, will be grounded with the result that the switch wipers 340 to 343, inclusive, will continue to step until such time as the test wiper 342 engages the normally grounded all-trunk busy conductor 363 which, in case all the trunks are busy, is now no longer grounded. Under this condition, when the switch wiper stops in engagement with this 75

set of bank contacts the test relay is energized and busy tone is transmitted to the calling subscriber. When test wiper 343 encounters the bank contact terminating conductor 363 from which ground has been removed, then the test relay 303 energizes in the same manner as previously described to transmit the busy tone back to the calling subscriber. The busy tone circuit may be traced from the busy tone source, wiper 340, tone condenser, armature 318, conductor 263, armature 215, normally closed contacts controlled by armature 216, conductor 160, and from thence back over the calling loop to the calling subscriber in the well known manner. When the delayed ground is connected to conductor 370, as previously described, switching relay 305 energizes and locks and at armature 327 open the circuit to relay 304, whereupon the latter relay deenergizes. When the calling subscriber hears the busy tone such subscriber will replace his receiver, thereby causing the deenergization of relays 306, 301, and 302, and the release of the local lineswitch and selector, as previously described. Test relay 303 likewise deenergizes to open the busy tone circuit and to cause the operation of stepping magnet 307 which in turn causes the deenergization of switching relay 305, after which stepping magnet 307 deenergizes and steps the wipers one step.

Returning now to the point where the toll operator is signalled and has answered, it will now be assumed that the toll operator is to extend this call back through the local exchange to the distant automatic exchange instead of to an exchange beyond the toll center, as previously described. At the time the operator has answered it will be remembered that the following relays are operated: relays 306, 301, 302, 303, 305, 209, 208, 201, 202, and 206. The operator after answering the call now momentarily grounds both conductors 360 and 361. Ground extending over conductor 360 short circuits the lower winding of relays 209 and 210, while ground over the conductor 361 holds the line relay 209 energized and causes the operation of differential relay 210. Differential relay 210, upon operating, at armature 241 completes the circuit for energizing differential dial-back relay 212 as follows: from ground by way of armature 239 and front contact, armature 241, armature 225, armature 244 and back contact, and through the lower winding of differential dial-back relay 212 to battery. At armature 246 relay 212 opens a further point in the circuit to the ringing machine start lead, at armature 247 prepares a point in the circuit through its upper winding, at armature 248 closes a circuit for maintaining its lower winding energized and for short circuiting the lower winding of relay 211 and at armature 249 closes a loop circuit through the dial-back lineswitch to cause the operation of line relay 610 thereat. The short circuit around the lower winding of relay 211 and the circuit for maintaining dial-back relay 212 in energized position may be traced as follows: from ground by way of armature 314, conductor 262, armature 248, lower winding of relay 211, lower winding of relay 212 and from thence by way of back contact and armature 244, armatures 225 and 241, and front contact and armature 239.

The circuit for energizing the line relay 610 of the dial-back lineswitch may be traced as follows: from ground by way of springs 614, conductor 275, armature 249, armature 240, right-hand operating winding of polarized shunt-field relay 204, back contact and armature 232, armature 250, conductor 276 springs 601, conductor 560, armature 526 and back contact, and through the upper winding of line relay 506 to battery. The operation of the dial-back lineswitch and local selector are similar to that previously described for the local lineswitch and local selector used by the calling local subscriber, and therefore only a brief description of the operations will be given. Line relay 506, upon energizing, at armature 524

ture 250, conductor 276, springs 613 and through the winding of line relay 610 to battery. Polarized shunt-field relay 204 does not energize over the above-traced circuit because the current flow in the operating winding is in the wrong direction. 5

The toll operator now disconnects ground from conductors 360 and 361, whereupon the differential relay 210 deenergizes since the short circuit is now removed from its lower winding. Relay 210, upon deenergizing, at armature 241 removes 10 the short circuit from around the lower winding of relay 211, whereupon the latter relay energizes in series with the lower winding of dial-back relay 212 over the circuit previously traced. Relay 211, upon energizing, at armature 242 prepares 15 a point in the locking circuit to switch-through relay 203, at armature 243 opens the circuit to trunk reversing relay 301, at armature 244 opens the original energizing circuit through the lower winding of dial-back relay 212 at its 20 back contact and at its front contact prepares a point in the circuit to the upper windings of relays 211 and 212, and at armature 245 opens a further point in the circuit to the stepping magnet 307. Trunk reversing relay 301 accordingly 25 deenergizes and at armatures 311 and 312 reverses the current back over the toll trunk conductors 360 and 361 to indicate to the toll operator that she may dial.

Returning now to the dial-back lineswitch at 30 a time when the circuit to the line relay 610 is completed. Relay 610, upon energizing, at armature 612 completes the circuit for the lower pull-down winding of plunger-coil 616 as follows: from ground at the master switch by way of conductor 660, front contact and armature 612, and through the lower pull-down winding of plunger coil 616 to battery. In response to the operation of the plunger coil 616 the plunger in the dial-back lineswitch is operated to plunge in on 40 an idle trunk and in this case, assuming that the trunk conductors 560 to 563 extend to another local selector similar to the selector shown in Fig. 5, the plunger will operate and close springs 601 to 604, inclusive. The operation of the plunger coil 616 also at springs 613 and 614 opens the circuit to line relay 610 and at spring 615 momentarily completes a circuit through the upper winding of coil 616 from ground by way of the front contact and armature 611, non-restricted 50 connector 680, springs 615, and through the upper winding of coil 616 to battery.

In order to avoid duplication of drawings it will be assumed that the local selector shown in Fig. 5 is now a different selector than the one 55 taken into use by the local subscriber, and that in response to the plunging of the dial-back lineswitch the following circuit is completed for line relay 506 of this local selector as follows: from ground through the normally closed springs controlled by armature 516, lower winding of line relay 506, back-contact and armature 530, conductor 563, springs 604, conductor 275, armature 249, armature 240, through the right-hand operating winding of polarized shunt-field relay 204, 65 back contact and armature 232, armature 250, conductor 276 springs 601, conductor 560, armature 526 and back contact, and through the upper winding of line relay 506 to battery. The operation of the dial-back lineswitch and local 70 selector are similar to that previously described for the local lineswitch and local selector used by the calling local subscriber, and therefore only a brief description of the operations will be given. Line relay 506, upon energizing, at armature 524

completes the circuit for energizing release relay 505 and at armature 525 prepares the test circuit for the polarized switching relay 507. Release relay 515, upon energizing, at armature 520 connects ground to conductor 561 to maintain the dial-back lineswitch in operated position after the line relay 610 deenergizes, at armature 521 prepares a point in the circuit to a point in the impulsing circuit to the vertical magnet 502 and 10 the series relay 504, and at armature 522 closes a circuit through the lower polarizing winding of switching relay 507 and completes the circuit for operating series relay 504. Series relay 504, upon energizing, at armature 516 substitutes ground 15 through the dial-back tone source for ground at the normally closed springs controlled by armature 516 in order to give the operator the dial tone, at armature 517 opens a point in the circuit to the release magnet, at armature 518 prepares the circuit for the vertical magnet 502 and 20 at its own upper winding, and at armature 519 opens the circuit to the rotary magnet 503. Dial tone is now transmitted back to the toll operator as follows: from grounded dial tone source, back 25 contact and cam spring 513, armature 516, lower winding of line relay 506, front contact and armature 530, conductor 563, springs 604, conductor 275, condenser C, armature 233, condenser C3, conductor 266, and from thence back over the 30 heavy talking conductors, as previously traced, to the toll operator.

When the toll operator hears dial tone she then dials the digit required to operate this other local selector to seize an idle trunk extending to 35 the distant automatic exchange and thereafter dials the called subscriber's number in the distant automatic exchange to complete the desired connection. In response to the first digit, or in this case the digit 6, line relay 209 in the dial-back 40 repeater follows the impulses and deenergizes six times. Each time line relay 209 deenergizes, the loop circuit extending through the line relay 506 in the local selector is opened at armature 240, while at armature 239 and its back contact a circuit is completed for energizing the series relay 205 and at the front contacts of armature 239 45 the circuit through the release relay 209 is momentarily opened but the latter relay, being of the slow-to-release type, maintains its armatures attracted throughout the impulsing series. The circuit for energizing series relay 205 may 50 be traced from grounded armature 239 and back contact, and armatures 235 and 224, through the winding of series relay 205 to battery. Series relay 205 is also of the slow-to-release type and 55 therefore maintains its armatures attracted throughout the impulsing period. At armatures 230 and 231 relay 205 opens the circuit extending back to the calling subscriber to prevent this subscriber from hearing the dial impulses and at 60 armature 232 short circuits the right-hand operating winding of the polarized shunt-field relay 204 in order to improve the impulsing circuit. Slow-to-release relay 205 falls back after each 65 dialling period. At armature 232 opens the direct loop to the dial-back switches and closes a loop in series with the right-hand operating winding of shunt field relay 204 and the resistance R1 in multiple; at armatures 230 and 231 reconnects 70 the calling subscriber. The non-inductive resistance R2 prevents completely opening the loop circuit to the dial-back switches during the transfer from the direct loop to the loop in series with relay 204. The non-inductive resistance R1 re-

duces the impedance of the loop to the dial-back switches.

In the local selector each time relay 506 de-energizes said relay at armature 524 completes a circuit for operating the vertical magnet 502 and for maintaining relay 504 in energized position, as previously described. The vertical magnet 502 in response to these impulses raises the wipers and shaft opposite the sixth level at which time the normal post springs are operated. The 10 off-normal springs close on the first vertical step of the shaft to prepare the circuit for the release magnet 501 at off-normal springs 510, to open the original energizing circuit of series relay 504 now held over its upper winding, and at off-normal springs 512 prepares a point in the circuit for the rotary magnet 503. After the impulsive period the slow-to-release series relay 504 de-energizes and at armature 516 disconnects dial tone and again reconnects ground. At armature 20 517 relay 504 prepares a point in the circuit to release magnet 501, at armature 518 opens a point in its own circuit, and at armature 519 completes the circuit for operating the rotary magnet 503. Rotary magnet 503, upon energizing, 25 steps the wipers into engagement with the first set of bank contacts in the sixth level and at interrupter contacts 515 interrupts its own circuit. The rotary magnet 503 continues to operate in the manner of a buzzer until such time 30 as the test wiper 541 finds battery potential on a test contact terminating an idle outgoing repeater to the distant automatic exchange, at which time the circuit for the polarized switching relay 507 is completed to stop further rotation of the switch wipers.

Since the local selector has been operated to the restricted level the circuit for operating the switching relay 507 now includes the operated normal-post springs and the non-restricted conductor 680 in the dial-back lineswitch as follows: from ground by way of armature 520, back contact and spring 523 of the busy key, conductor 561, springs 602, non-restricted conductor 680, springs 603, conductor 562, front contact and 45 spring 531, of the normal-post springs, upper winding of switching relay 507, armature 525, test wiper 541, conductor 157, normally closed springs controlled by armature 112, armature 113 and back contact, armature 120 and back contact, and through the resistance R to battery. Polarized switching relay 507 very quickly energizes over the above-traced circuit and at armature 527 opens the circuit to the rotary magnet to prevent further rotary operation of the wipers. 55 At armatures 526 and 530 switching relay 507 disconnects the line relay 506 and extends the loop from the dial-back repeater to line relay 102 in the outgoing repeater shown in Fig. 1. At armature 528 relay 507 closes a holding circuit 60 through its lower polarizing winding independent of ground at armature 522 and ground at armature 520, and at armature 529 prepares a circuit to hold itself in energized position and maintain the preceding switches operated when ground is 65 sent back from the repeater. Line relay 506, upon deenergizing, at armature 524 prepares a point in the circuit to the release magnet 501 and also opens another point in the circuit to the release relay 505, and at armature 525 opens the 70 circuit to the upper operating winding of the switching relay 507 which relay is now held in operated position through its lower winding alone. Relay 505, being slow to release, does not deenergize until after ground is sent back over 75

conductor 157 from the outgoing repeater at which time this ground extends by way of wiper 541, armature 529, and armature 528 to hold relay 507 in operated position, and which ground likewise extends by way of the busy key over conductor 561 to maintain this local selector busy and to hold the dial-back lineswitch in operated position. When release relay 505 deenergizes after an interval, said relay at armature 520 disconnects ground from conductor 561 now grounded from the outgoing repeater, at armature 521 prepares a further point in the circuit to the release magnet 501, and at armature 522 likewise disconnects ground from the lower winding of switching relay 507 which, however, is also grounded from the repeater, as previously described.

Line relay 102 in the outgoing repeater is energized over the following circuit when the switching relay 507 in the local selector switches through: from ground through the lower winding of line relay 102, through the lower left-hand winding of repeating coil RC, normally closed springs controlled by armature 111, conductor 156, wiper 542, front contact and armature 530, conductor 563, back through the loop previously traced through the dial-back lineswitch and dial-back repeater to conductor 560, armature 526 and front contact, wiper 540, conductor 155, normally closed springs controlled by armature 110, through the upper left-hand winding of repeating coil RC and through the upper winding of line relay 102 to battery. At armature 113 line relay 102 completes the circuit for energizing release relay 104, and at armature 114 prepares a point in the loop circuit extending to the distant automatic exchange. Release relay 104, upon energizing, at armature 115 completes the circuit through the polarizing right-hand winding of polarized shunt field relay 103, at armature 116 completes the circuit for energizing switching relay 105, and at armature 117 connects ground to conductor 157 by way of the normally closed springs controlled by armature 112 to maintain the switching relays 507 in the local selector energized and to maintain the dial-back lineswitch operated. Switching relay 105, upon energizing, at armatures 118 and 121 disconnects the rotary incoming lineswitch from the outgoing trunk conductors at back contacts and at the front contacts of these armatures completes the loop circuit extending to the distant automatic exchange. At armature 119 relay 105 opens a point in the circuit to the reversing relay 101, and at armature 120 prepares a substitute circuit for grounding armature 117 during the interval when relay 104 is released and relay 105 is falling back.

The loop circuit extending to the distant automatic exchange may be traced from conductor 151, armature 118 and front contact, upper right-hand winding of repeating coil RC, through the operating winding of the polarized relay 103, lower right-hand winding of repeating coil RC, pulsing armature 114, front contact and armature 121, and by way of trunk conductor 153 to the distant automatic exchange. The closure of this loop circuit in the distant automatic exchange operates the line relay therein to prepare the automatic switches for operation. The flow of current through the operating winding of the polarized shunt field relay 103 is in such a direction that the relay does not operate its armature 133 at this time. The toll operator now dials the digits of the called subscriber's number

in the distant automatic exchange, whereupon line relay 209 in the dial-back repeater at armature 240 interrupts the circuit to the line relay 102 in the outgoing repeater, whereupon the line relay 102 at armature 114 repeats the impulses over the trunk conductors 151 and 153 to operate the automatic switches in the distant exchange to complete the desired connection. At armature 113 line relay 102 intermittently opens the circuit to slow-to-release relay 104 but the latter relay, due to its slow-release characteristics is maintained energized during the impulsive period.

When the called party in the distant automatic exchange answers the flow of current is reversed over the trunk conductor 151 and 153 through the operating winding of polarized shunt field relay 103 to cause this polarized relay to operate its armature 133. At armature 133 relay 103 completes the circuit for the reversing relay 201, whereupon the latter relay at armature 112 connects direct ground to conductor 157 to maintain the local selector and dial-back lineswitch in operated position. At armatures 110 and 111 reversing relay 101 reverses battery back over conductor 155 and 156 for operating the shunt field polarized relay 204, which it will be remembered is included in the loop circuit extending to the dial-back switches.

The reversal of current through the operating winding of polarized relay 204 causes the operation of this relay whereupon at armature 227 a circuit is closed through the winding of switch-through relay 203 and through the upper winding of line reversing relay 201. At armature 228 relay 204 again completes the circuit for energizing trunk reverse relay 301 and at armature 229 shorts the resistance R2 at the back contact and armature 232. At armature 223, relay 203 upon energizing prepares a point in its own locking circuit, at armature 224 opens the circuit to series relay 205, at armature 225 opens the circuit through the upper windings of relays 211 and 212, at armature 222 disconnects one of the multiple grounds from the lower terminal of test relay 313, at armature 226 and back contact removes the resistance R1 from in multiple with the operated winding of relay 204 to improve transmission, and at the front contact thereof connects the operating winding of the polarized relay 204 directly across the trunk conductors 275 and 276 independent of armature 240 to prevent further interruption of the loop to the dial-back switches when line relay 209 is deenergized. The trunk reversing relay 301 is energized over the following circuit: from ground by way of armature 329, conductor 265, armature 243 and front contact, armature 228, conductor 264, and through the winding of trunk reversing relay 301 to battery. At armatures 311 and 312 trunk reversing relay 301 reverses battery back over the toll trunk conductors 360 and 361 to give the toll operator answering supervision in the well known manner.

When the toll operator receives the answering supervision indicating that the distant automatic called subscriber has answered, the toll operator will disconnect by opening the circuit to relays 209 and 210. Relay 209 accordingly deenergizes and at armature 239 and front contact opens the circuit to release relay 208. At armature 239 and back contact line relay 209 completes the locking circuit for relay 203 by way of armatures 242 and 223, and at armature 240 opens the previous loop impulsive circuit to the dial-back which loop is 75

now closed through armature 225 and front contact. Slow-to-release relay 208, upon deenergizing, at armature 236 removes one of the multiple grounds connected to conductor 161 and to the polarizing winding of relay 204, at armature 237 opens the locking circuit of tone relay 206 and the circuit through the lower winding of line reversing relay 201 which, however, is maintained in operated position over its upper winding, and at 10 armature 238 opens the circuit to test relay 303. Tone relay 206, upon deenergizing, at armature 233, removes the short circuit from the upper winding of impedance 207. Test relay 303, upon deenergizing, at armature 317 and back contact 15 completes the short circuit around the lower winding of switching relay 305 and also completes the circuit for energizing stepping magnet 307, as previously described. At armature 318 relay 303 opens a point in the ring-back circuit, at armature 319 opens a point in its own locking circuit as well as preparing the automatic stepping circuit for stepping magnet 307, and at armature 320 prepares another point in the stepping circuit to stepping magnet 307. The circuit for energizing stepping magnet 307 may be traced as follows: from grounded armature 325 and front contact, armature 317 and back contact, and through the winding of stepping magnet 307 to battery. Stepping magnet 307 operates its pawl preparatory to 30 stepping the wipers of the associated switch, and at interrupter springs 332 opens the circuit through the lower winding of switching magnet 305, as well as opening the short circuit around the lower winding of switching relay 305. Relay 35 305 deenergizes after an interval and at armature 325 opens the circuit to stepping magnet 307 to allow the stepping magnet to deenergize and step the wipers one step. At armatures 326 and 331 relay 305 upon deenergizing opens the circuit extending to the toll operator over the toll trunk, at armature 327 again establishes the circuit for 40 energizing ringing relay 304, and at armature 328 removes ground from test wiper 343 and conductor 362 to make this toll trunk available for other 45 calls. The operation of ringing relay 304 is without effect at this time because switching relay 305 is not in operated position. The dial-back repeater is now operatively disconnected from the toll trunk which is free to be seized and used on 50 other calls.

The calling local subscriber and the called distant automatic subscriber may now converse over the following talking circuit: from local subscriber A over conductors 670 and 671, springs 651 and 55 654, conductors 560 and 563, through the first local selector by way of armatures 526 and 530 and front contacts, wipers 540 and 542, conductors 160 and 162, armatures 218 and 215 and their front contacts, armatures 231 and 230 and their back contacts, condensers C1 and C, back contact and armature 232, and front contact and armatures 250 and 249, conductors 276 and 275, dial-back line switch contacts 601 and 604, the talking conductors extending to the second local selector 60 which, in this case, we are assuming to be a selector like the local selector in Fig. 5, and thence by way of armatures 526 and 530 and their front contacts, wipers 540 and 542, conductors 155 and 156, front contacts and armatures 110 and 111, 65 and through the left-hand windings of the repeating coil RC, and from thence through the right-hand winding of the repeating coil RC and condenser, armature 114, front contacts and armatures 118 and 121, and over trunk conductors 151 70 and 153, and through the automatic switches in 75

the distant automatic exchange to the called subscriber. Talking battery to the called subscriber is furnished from the automatic switches in the distant automatic exchange and talking battery for the local calling subscriber is furnished 5 through the windings of relay 306.

After conversation and in response to the called automatic subscriber replacing his receiver, the current flow over trunk conductors 151 and 153 is reversed in the well known manner. Due to 10 this reversal of current in the operating winding of polarized relay 103, relay 103 deenergizes and at armature 133 opens the circuit to the reversing relay 101, whereupon the latter relay at armatures 110 and 111 reverses battery back through 15 the operating winding of polarized relay 204. This reversal of current in the operating winding of polarized relay 204 causes the deenergization of the latter relay. At armature 227 relay 204 disconnects one of the ground connections from 20 the upper winding of line reversing relay 201 and switch-through relay 203 which relays, however, are still maintained energized from ground at armature 239 by way of armatures 242 and 223. At armature 228 relay 204 opens the circuit to 25 trunk reversing relay 301 to restore the latter relay to its normal position, and at armature 229 removes the shunt around armature 232.

When the calling subscriber hangs up the circuit to battery feed relay 306 is opened whereupon this relay accordingly deenergizes. At armature 330 relay 306 opens the circuit to hold relay 302 and ring relay 304. Relay 302, upon deenergizing, at armature 313 again connects the resistance R5 and battery to the release trunk 161 35 through the lower winding of impedance 207 at its back contact and at its front contact removes one of the multiple grounds from the conductor 161. At armature 314 relay 302 disconnects the remaining ground from the release 40 trunk conductor 161 to free the local selector and lineswitch extending to the calling line, and also opens the circuits to relays 211 and 212 and the polarizing winding of relay 204. Relay 212, upon deenergizing, at armatures 249 and 250 opens the 45 loop circuit extending to the dial-back switches to permit the dial-back switches including the dial-back lineswitch and the second local selector to release. Relay 211, upon deenergizing, at armature 242 opens the circuit to switch-through 50 relay 203 and line reversing relay 201 to cause these relays to deenergize. At armature 243 relay 211 prepares the original energizing circuit of relay 301, at armature 244 prepares the original energizing circuit of dial-back relay 212, and at 55 armature 245 prepares a point in the stepping circuit to stepping magnet 307. Switch-through relay 203, upon deenergizing, at armature 223 opens a point in its own locking circuit, at armature 224 prepares a circuit to relay 205, at armature 225 again prepares the circuit for relay 212, at armature 222 grounds conductor 273 to prepare the circuit for test relay 303, and at armature 226 connects the resistance R4 in bridge of the 60 operating winding of polarized relay 204. Relay 201, upon deenergizing, at armature 231 again grounds the all-trunk-busy conductor at its back contact and at its front contact opens the circuit to timing relay 202, at armature 215 prepares a 65 point in the ring-back circuit, at armature 217 places a shunt around the upper winding of impedance 207, and at armatures 216 and 218 restores the talking conductors to normal position. Timing relay 202 upon energizing at 70 75

armature 221 opens a point in the circuit to tone relay 206.

The disconnection of ground from release conductor 161 by the deenergization of release relay 302 opens the holding circuit to the switching relay 507 in the first local selector and to the plunger coil 646 of the local line switch, whereupon the relay and coil deenergize. Relay 507, upon deenergizing, completes the circuit for the release magnet 591 to cause the selector to release in the same manner as previously described. The deenergization of the plunger coil 646 in the local lineswitch causes the local lineswitch to restore in the well known manner.

15 When the loop to the dial-back lineswitch is opened at armatures 249 and 250 by the deenergization of relay 212, relay 102 in the outgoing repeater deenergizes. Relay 102, upon deenergizing, at armature 113 opens the circuit of release relay 104 and at armature 114 opens the loop extending to the distant automatic exchange to release the automatic switches therein in the well known manner. Release relay 104, upon deenergizing, at armature 115 opens a circuit extending 20 through the polarizing winding of relay 103, at armature 116 opens the circuit to switching relay 105, and at armature 117 substitutes the ground at armature 120 for the ground at armature 117 for maintaining the release trunk 157 grounded by 25 means of which the second local selector and the dial-back lineswitch is maintained in operated position. Switching relay 105, upon deenergizing, at armatures 118 and 121 connects the trunk conductors 151 and 153 to the incoming rotary lineswitch, at armature 120 and front contact disconnects ground from release trunk conductor 157 to open the circuit to the switching relay in the second local selector and the plunger coil in the dial-back lineswitch, and at the back contact 30 connects battery through the resistance R so that the outgoing repeater may be seized for other outgoing calls.

When ground is disconnected from release trunk conductor 157 the second local selector seized by the dial-back lineswitch and this lineswitch are released by the deenergization of the switching relay, similar to switching relay 507, and by the deenergization of the plunger coil 616. Since the release of the dial-back lineswitch and 35 the second local selector seized by such lineswitch is similar to the release of the local lineswitch and the first local selector, a further description of the releasing operation will not be given. All of the apparatus now used in extending 40 and completing a call between a local calling subscriber to a distant called automatic subscriber by the aid of the toll operator are now in normal position and may be used on subsequent calls.

It will now be assumed that an automatic subscriber in the distant automatic exchange, desires 45 to talk with an automatic subscriber in the local exchange. In this case the distant automatic subscriber operates the distant automatic switches to seize one of the idle trunks extending to the local exchange and it will therefore be assumed that the trunk conductors 151 and 153 are the 50 trunk conductors engaged by the distant automatic switches in initiating this call. When this trunk is seized, a bridge is closed across the conductors 151 and 153 at the distant automatic exchange to complete the energizing circuit for line 55 relay 108 of the incoming lineswitch as follows: from ground through the lower winding of line relay 108, back contact and armature 124, back contact and armature 121, trunk conductor 153

through the loop in the distant automatic exchange to trunk conductor 151, armature 118 and back contact, armature 122 and back contact, and through the upper winding of line relay 108 to battery. At armature 127 relay 108 completes 5 an energizing circuit for the stepping magnet 109 from grounded armature 126 and at armature 128 completes the circuit for energizing the slow-to-operate relay 107. Stepping magnet 109, upon energizing, positions its pawl preparatory to stepping the wipers of the incoming rotary lineswitch, and at interrupter springs 129 opens a point in its own automatic stepping circuit. After an interval slow-to-operate relay 107 energizes and at armature 125 prepares a point in the automatic 10 stepping circuit of magnet 109. At armature 126 and back contact relay 107 opens the circuit to stepping magnet 109 and its front contact prepares a point in the energizing circuit of switching relay 106 and also completes the circuit for 15 energizing reversing relay 101 by way of armature 119. Reversing relay 101 at armature 112 connects ground to the release trunk conductors 152 and 157 to mark this outgoing repeater busy to the monitoring and local selectors. Stepping 20 magnet 109, upon deenergizing, steps the wipers 130 to 132, inclusive, one step into engagement with the next set of bank contacts, and at armature 129 completes a circuit for energizing switching relay 106 or for short circuiting this latter 25 relay dependent upon the idle or busy condition of the dial-back repeater terminating in this set of bank contacts.

In case the dial-back repeater terminating in this set of bank contacts is in use, then ground 30 will be connected to the release conductor 161 whereupon a circuit may be traced for short-circuiting the switching relay 106 as follows: from grounded release trunk conductor, test wiper 131, armature 123 and back contact, armature 125, 35 through the winding of switching relay 106 to ground at armature 126. The switching relay 106 is prevented from operating over this circuit and this same ground from release trunk conductor extends through the interrupter springs 40 129 and the winding of the motor magnet 109 to energize the magnet. Motor magnet 109 thereupon energizes from ground engaged by the test wiper 131 and causes the wipers to step on the deenergization thereof to engage another set of 45 bank contacts terminating another dial-back repeater. This stepping operation continues as long as test wiper 131 encounters a grounded bank contact.

As soon as the test wiper 131 engages a bank 50 contact having no ground potential thereon then the switching relay 106 energizes in series with the marginal stepping relay 109 as follows: ground by way of armature 126 and front contact, winding of switching relay 106, interrupter spring 55 129, and through the winding of stepping magnet 109 to battery. Due to the high resistance of the winding of switching relay 106 stepping magnet 109 is not energized in this circuit. Switching relay 106, upon energizing, at armature 123 connects ground by way of armature 126 and test wiper 131 to release trunk conductor 161 to make 60 this dial-back repeater busy to the local selectors, and at armatures 122 and 124 and back contacts disconnects line relay 108 and at the front contacts connects the trunk conductors 151 and 153 to trunk conductors 170 and 172, whereupon a circuit is completed for energizing the battery feed relay 306 as follows: from ground by way of the upper winding of relay 306, conductor 268, nor- 65 70 75

mainly closed springs controlled by armature 218, conductor 172, wiper 132, front contact and armature 124, back contact and armature 121, conductor 153, through the distant loop, conductor 151, armature 118 and back contact, armature 122 and front contact, wiper 130, conductor 170, normally closed springs controlled by armature 216, conductor 269, and through the lower winding of battery feed relay 306 to battery.

10 Relay 306, upon energizing, at armature 329 completes the energizing circuit for trunk reversing relay 301, and at armature 330 completes the circuit for energizing hold relay 302 and ring relay 304, as previously described. At armature 313, 15 relay 302 grounds the test conductor 161 by way of the busy key springs 334, conductor 261, and the lower winding of impedance 207 to hold the switching relay 106 in the incoming lineswitch in operated position after the release relay 107 deenergizes which it does shortly after the release 20 of line relay 108. This ground on release trunk conductor 161 extends through wiper 131, armature 123 and front contact to switching relay 106.

Line relay 108 deenergizes in response to the 25 operation of switching relay 106, and at armature 128 opens the circuit to release relay 107 and at armature 127 opens the original energizing circuit of stepping magnet 109. Release relay 107 in addition to being slow to operate is likewise 30 slow to release and therefore ground at armature 126 is not removed from the winding of switching relay 106 until ground is sent back over test conductor 161, as previously described.

Relay 302 also at armatures 315 and 316 prepares the circuit as previously described for operating the test relay 303 in case the wipers of the switch associated with the dial-back repeater are in engagement with an idle trunk or complete the circuit for energizing the marginal stepping magnet 307 in case the test wiper 343 engages a grounded bank contact indicating that this particular toll trunk is busy. Since this operation is the same as previously described it is not thought necessary to give the detailed operations thereof. When test relay 303 energizes in 45 response to the associated switch engaging an idle toll trunk test relay 303 energizes and at armature 318 connects the ring-back tone to the calling subscriber over the following circuit: from interrupted generator connected to the multiple 50 connected bank contacts accessible to wiper 340 through the ring-back condenser, armature 313, conductor 263, armature 215, conductor 170, wiper 130, front contact and armature 122, armature 118, conductor 153, to the distant automatic exchange.

At armature 320, relay 303 connects ground by way of armature 22, conductor 273, and armature 315 to test wiper 343 to ground conductor 362 60 thereby marking this toll trunk busy to other dial-back repeaters. Test relay 303 also at armature 319 locks itself in the same manner as previously described. At armature 317 relay 303 connects the high resistance common relay 371 65 in series with the lower winding of switching relay 305 and the winding of stepping magnet 307. Relay 371 alone energizes over this circuit to cause the operation of the A. C. relay 276 which in turn at armature 315 completes the energization of relay 374. After an interval relay 374 70 connects ground to armature 373 and conductor 370 whereupon the switching relay 305 is energized as previously described. Switching relay 305 therefore energizes a short time after the 75 energization of test relay 303 and at armatures

326 and 331 connects generator out over the toll trunk conductors to signal the toll operator. Slow-to-release relay 304 deenergizes shortly after the operation of switching relay 305 to disconnect ringing current and connect the toll 5 trunk to the windings of differential relay 210 and line relay 209.

When the toll operator answers in response to the splash of ringing current, line relay 209 energizes and at armature 239 completes a circuit 10 for energizing relay 208. Relay 208 at armature 236 grounds the release trunk conductor 161 through the lower winding of impedance 207, at armature 237 completes the circuit through the lower winding of reversing relay 201, and at armature 238 grounds conductor 274 to hold the test relay 303 in operated position. Relay 201 energizes and reverses battery back to the calling distant automatic exchange at armatures 216 and 218, opens the ring-back circuit at armature 215, and at armature 213 completes a circuit for the timing relay 202. Relay 202 operates and vibrates its weighted spring 220, whereupon slow-to-operate relay 206 is energized after a predetermined time. The circuits for operating relays 25 209, 208, 201, and 202 and 206 are the same as previously described and have not therefore been traced in detail.

A talking circuit is now completed between the distant automatic subscriber and the toll operator as follows: trunk conductors 151 and 153, armatures 118 and 121 and their back contacts, armatures 122 and 124 and front contacts, wipers 130 and 132, conductors 170 and 172, armatures 230 and 231, armature 233, condensers C3 and 35 C2, conductors 266 and 267, armatures 312 and 311 and front contacts, resting contacts and armatures 323 and 322, armatures 331 and 326, wipers 342 and 341, and by way of the toll trunk conductors 361 and 360 to the toll operator. Talking 40 battery to the toll operator is furnished through the windings of line relay 209 while talking battery through the windings of relay 306 is furnished to the distant automatic subscriber.

The toll operator may extend the call to a 45 distant exchange or may call back through the dial-back switches in this local exchange by momentarily unbalancing the line to operate differential relay 210 and thereafter dial the local subscriber's number to cause the operation of the 50 dial-back lineswitch, the local selector and connector to complete the connection to the desired local line in the same manner as previously described. The talking circuit between the distant calling subscriber and the local called subscriber 55 extends over the trunk conductors 151 and 153, conductors 170 and 171 to armatures 230 and 231, as previously traced, and thence by way of condensers C and C1, armature 232 and back contact, armatures 249 and 250, conductors 275 60 and 276 and through the dial-back lineswitch, local selector, and local connector to the called local subscriber's line. After completing the connection over the dial-back lineswitch, the local selector and connector, and the called subscriber 65 has answered, the toll operator may disconnect and free her toll trunk for other uses in the same manner as previously described. After conversation, and responsive to the distant calling subscriber and the local called subscriber replacing 70 their receivers the dial-back lineswitch, selector and connector in the local exchange and the dial-back repeater are released in the same manner as previously described when the calling subscriber opens the circuit to relay 306. When the dial- 75

back repeater has released ground is removed from conductor 161, thereby opening the circuit of switching relay 106. The removal of ground from release trunk conductor 161 also opens the circuit through reversing relay 101 whereupon the latter relay at armature 112 disconnects ground from release trunk conductors 152 and 157 to again mark this outgoing repeater as being idle. The restoration of the switching relay 106 again prepares the incoming lineswitch for use on further incoming calls over this trunk conductor.

In case the toll operator dials the wrong number, if a dead number is encountered, or if for some other reason the toll operator is unable to complete the desired connection she may release the dial-back switches by momentarily grounding both conductors 360 and 361 to operate the differential relay 210 a second time. In order to describe this operation it will be assumed that the dial-back lineswitch in Fig. 6 and the local selector in Fig. 5 have been operated and for some reason due to wrong dialling or otherwise the desired connection cannot be completed. In the dial-back repeater in Figs. 2 and 3 it will be remembered that certain relays will be operated at this time before the called party answers, namely: relays 201, 202, 206, 208, 209, 211, 212, 302, 313, 305, and 306. Now when the toll operator grounds the toll conductors 360 and 361 differential relay 210 is again operated in the same manner as previously described. Since relays 211 and 212 are operated at this time the operation of armature 241 by differential relay 210 completes a circuit through the upper windings of relays 211 and 212 as follows: from grounded armature 239 and front contact, armature 241, armature 245, armature 244 and front contact through the upper winding of relay 211 and by way of armature 247 through the upper winding of differential dial-back relay 212. The circuit traced through the upper winding of relay 211 maintains this relay in energized position, while the circuit through the upper differential winding of dial-back relay 212 causes the differential dial-back relay 212 to deenergize, since the upper and lower windings now oppose each other. At armatures 247 and 248 relay 212 simultaneously opens the circuit through both its windings and in addition at armature 248 opens the circuit through the lower winding of relay 211 which relay, however, at this time is held energized through its upper winding alone. At armatures 249 and 250 relay 212 opens the loop extending to the dial-back lineswitch and local selector and connector to cause these switches to release in the same manner as previously described. The toll operator now removes the unbalancing ground condition from conductors 360 and 361, whereupon differential relay 210 deenergizes. At armature 241 relay 210 opens the circuit through the upper winding of relay 211, whereupon this relay now deenergizes. Relay 211 at armature 243 completes the original energizing circuit of trunk reversing relay 301 which thereupon operates and reverses battery to the toll operator as previously described.

The toll operator may now reoperate the dial-back lineswitch by again connecting ground to both conductors 360 and 361 to reenergize the differential relay 210. The operation of relay 210 at armature 241 causes the operation of relay 212 which at armatures 249 and 250 closes a loop circuit to the dial-back lineswitch to cause it to plunge and seize an idle local selector, as pre-

viously described. At armature 248 relay 212 completes the circuit for operating relay 211 when the short circuiting ground is removed by the deenergization of the differential relay 210 as previously described. The operation from here on is the same as previously described.

From the foregoing it will be seen that when the toll operator completes either incoming or outgoing calls between the local and distant automatic subscribers' lines, the toll operator is disconnected from these established connections and it is therefore desired to provide the toll operator with some means for ascertaining the idle or busy condition of the trunk lines connecting the distant and local automatic exchanges. The monitor selector shown in Fig. 4 is therefore provided in order for the toll operator to determine the idle or busy condition of the trunk lines connecting the two automatic exchanges. Assuming now that the toll operator wants to test the idle or busy condition of the trunk lines connecting the two automatic exchanges, then the toll operator will select one of her toll trunks extending to the local automatic exchange and in this case it will be further assumed that the trunk conductors 360 and 361 are the conductors of the trunk line selected. The toll operator in selecting this trunk line throws a bridge across the conductors 360 and 361 thereby completing a circuit for energizing line relay 620 of the incoming toll lineswitch as follows: from ground through springs 624, conductor 361, through the toll operator's bridge, conductor 360, springs 623 and through the winding of line relay 620 to battery. Since the operation of the incoming toll lineswitch is similar to both the dial-back lineswitch and local lineswitch, the operation of line relay 620 causes the plunger coil 626 to operate and select an idle local selector. Assuming further that the local selector in Fig. 5 is the selector seized by the plunging of the incoming toll lineswitch. When the toll operator hears dial tone transmitted from the seized selector, she will operate the local selector opposite the eighth level to seize the monitor selector in Fig. 4 in the same manner as previously described.

When the local selector switches through in response to the operating of switching relay 507, line relay 406 in the monitoring selector is energized over the following circuit: from ground through the lower winding of line relay 406, normally closed springs controlled by armature 425, conductor 462, wiper 542, front contact and armature 530, conductor 563, contact 635, conductor 361, through the bridge at the toll operator's position, conductor 360, springs 631, conductor 560, armature 526 and front contact, wiper 540, conductor 460, normally closed contacts controlled by armature 423, and through the upper winding of line relay 406 to battery. At armature 428 line relay 406 completes the circuit for the slow-to-release relay 405. At armature 426 relay 405 connects ground to release trunk conductor 461 to maintain the polarized switching relay 507 and the pull-down coil 626 in operated position to maintain the local selector and incoming toll line switch in operated position, and at armature 427 connects ground to armatures 414 and 419.

The toll operator now dials the digit 1 in order to supervise the first trunk line connecting the two automatic exchanges. In response to this digit, or digit 1, line relay 406 deenergizes and at armature 428 completes the circuit for energizing slow-to-release relay 403 as follows: from ground

by way of armature 428 and back contact, armature 429, and through the winding of slow-to-release relay 403 to battery. At armature 421 relay 403, upon energizing, opens the circuit of reversing relay 404, and at armature 422 completes a circuit through the upper winding of trunk No. 1 relay 402 to operate this relay in its first step to close its "X" contact at armature 419. This circuit may be traced as follows: from ground by way of armature 428 and back contact, armature 429, armature 422, armature 418 and back contact, and through the upper winding of relay 402 to battery. Relay 402 operates its armature 419 to complete a holding circuit for its upper winding and at the same time short circuits its lower winding from ground at armature 427 to ground at armature 428. When line relay 406 energizes after this impulse, ground at armature 428 is removed from the winding of series relay 403 and the windings of relay 402, whereupon the two-step relay 402 energizes in its second step over the following circuit: from ground by way of armature 427, armature 419, through the lower winding of two-step relay 402 and through the upper winding to battery. Relay 402 operates its remaining armatures and at armatures 416 and 420 connects the talking conductors 460 and 462 by way of armatures 411 and 415 and back contacts to conductors 151 and 153 extending to the distant automatic exchange. At armature 417 two-step relay 402 prepares a point in the circuit to the reversing relay 404. At armature 418 relay 402 prepares a point in the circuit for energizing trunk No. 2 relay 401. Shortly after the impulsive period, series relay 403 deenergizes and at the normally closed springs controlled by armature 421 completes the circuit for energizing the reversing relay 404 in case the first trunk line to the distant automatic exchange is busy. In this case ground will be connected to test conductor 152, thereby completing the energizing circuit for relay 404; from grounded conductor 152, back contact and armature 412, armature 417, normally closed springs controlled by armature 421, and through the winding of reversing relay 404 to battery. At armature 424 relay 404 prepares a locking circuit for itself and at armatures 423 and 425 reverses battery from the windings of the line relay 406 back over the toll trunk conductors in order to advise the operator that the first trunk line is busy. If desired, the toll operator may converse with the subscribers in the established connection or may camp on this connection until such time as the subscribers release whereupon ground is removed from conductor 152 to cause the deenergization of reversing relay 404 which thereupon again reverses battery back over the talking conductor to the toll operator advising such operator that the first trunk line is now idle and may be used on other calls.

If desired the toll operator may transmit another impulse to line relay 406 to test the idle or busy condition of the second trunk line. In response to this impulse line relay 406 again deenergizes and again completes the circuit for series relay 403 and at the same time completes the circuit for energizing two-step relay 401 in its first step to operate armature 414. The circuit for operating relay 401 in its first step may be traced as follows: from ground by way of armature 428 and back contact, armature 429, armature 422, armature 418 and front contact, armature 413 and back contact, through the upper winding of relay 401 to battery. At this time relay

401 operates only its armature 414 to complete a short circuit around its lower winding extending from ground at armature 427 and ground at armature 428. When line relay 406 energizes after this impulse, the circuit to series relay 403 is opened and the short circuit around the lower winding of two-step relay 401 is removed with the result that relay 401 operates through its second step to operate its remaining armatures. When series relay 403 energized in response to the second impulse, said relay at armature 421 completed the locking circuit for reversing relay 404 and at armature 422 completed the previously traced circuit for relay 401. At armature 412 relay 401, upon operating through its second step, disconnects test conductor 152 of the first trunk and connects up test conductor 152' of the second trunk and at armatures 411 and 415 disconnects the talking conductors of the first trunk and connects up the talking conductors of the second trunk. At armature 413 relay 401 opens the original energizing circuit to upper winding of relay 401 and transfers the impulsive circuit to a succeeding relay in case there are more than two trunks connecting the two automatic exchanges. Shortly after the second impulse transmitted by the toll operator, series relay 403 deenergizes and at armature 421 connects the reversing relay 404 to the test conductor 152'. In case the second trunk is busy ground on conductor 152' will maintain the reversing relay energized to maintain the reversed battery connection to the toll operator, thereby advising the toll operator that the second trunk is likewise busy. In case the second trunk line is not busy then no circuit is completed for reversing relay 404 with the result that relay 404 deenergizes and restores normal talking connections to the toll trunk thereby advising the operator that the second toll trunk is idle. From the foregoing it is therefore seen that by use of the monitor selector the toll operator is enabled to connect with the trunk lines connecting the two automatic exchanges regardless of their idle or busy condition and may converse thereover in case the trunk lines are in use.

Incoming toll calls from the toll switching center to local automatic subscribers are handled through the incoming toll lineswitch and the local selector and connector, while incoming toll calls from the toll switching center to the distant automatic exchanges are handled by the incoming line switch, local selector, and the outgoing repeater to the distant automatic exchange. The operation of the local selector and outgoing repeater is the same as previously described, except in this case no dial-back repeater is included in the circuit as the local selector when used by the toll operator connected with the outgoing repeaters direct.

Having described the invention, what is considered to be new and is desired to be protected by Letters Patent is set forth in the following claims.

What is claimed is:

1. In a telephone system, a distant exchange, a local exchange, and a toll exchange, trunk lines connecting the distant and local exchanges, dial-back repeaters in the local exchange, a hunting switch individual to each said trunk line having access to said repeaters, toll trunk lines connecting the local and toll exchanges, a selecting switch individual to each said repeater having access to said toll trunk lines, automatic subscribers' lines terminating in said local exchange, local

- connectors in said local exchange having access to said local lines, a local selector in said local exchange having access to said repeaters, said local connectors and to said trunk lines connecting the distant and local exchanges, and means whereby said local selector is accessible from said local subscribers' lines, said toll trunk lines, and said repeaters.
2. In a telephone system, a distant exchange, a local exchange, and a toll exchange, trunk lines connecting the distant and local exchanges, dial-back repeaters in the local exchange, a hunting switch individual to each said trunk line having access to said repeaters, toll trunk lines connecting the local and toll exchanges, a selecting switch individual to each said repeater having access to said toll trunk lines, automatic subscribers' lines terminating in said local exchange, local connectors in said local exchange having access to said local lines, a local selector in said local exchange having access to said repeaters, said local connectors and to said trunk lines connecting the distant and local exchanges, means whereby said local selector is accessible from said local subscribers' lines, said toll trunk lines, and said repeaters, and means for restricting said selector from connecting with any one of the trunk lines connecting the local and distant exchanges when taken into use over a calling local subscriber's line.
3. In a telephone system, a distant exchange, a local exchange, and a toll exchange, dial-back repeaters in the local exchange, trunk lines connecting the distant and local exchanges and having access to said repeaters, toll trunk lines connecting the local and toll exchanges and accessible from said repeaters, subscribers' lines terminating in the local exchange, local connectors having access to said subscribers' lines, a selector in said local exchange having access to said repeaters, said trunk lines connecting the local and distant exchanges, and said local connectors, said selector accessible to said local subscribers' lines, said toll trunk lines, and said repeaters, and means for restricting said selectors from connecting with any one of said trunk lines connecting the local and distant exchanges when taken into use over a calling local subscriber's line.
4. In a telephone system, two automatic exchanges, subscribers' lines terminating at each of said exchanges, trunk lines interconnecting said exchanges, a toll exchange, a toll trunk line interconnecting one of said automatic exchanges and said toll exchange, means whereby subscribers on lines terminating at either of said exchanges may complete their own local connections in their respective exchanges independently of said toll exchanges and without the aid of an operator, means for seizing said toll trunk line and for signalling the operator thereover in response to a call by a subscriber in either automatic exchange initiating a call to a subscriber in the other automatic exchange, means controlled by the operator back over said toll trunk line for extending the connection to the desired called subscriber's line in said other automatic exchange, means for freeing said toll trunk line for other use while maintaining the connection between the calling and called lines, and means for preventing the completion of calls between said automatic exchanges independently of said operator controlled means.
5. In a telephone system, a local exchange, a distant exchange, and a toll exchange, local subscribers' lines terminating in the local exchange, and distant subscribers' lines terminating in the distant exchange, a dial-back repeater in the local exchange, a toll trunk connecting the local and toll exchanges and accessible to said repeater, means responsive to a call by either a local or a distant subscriber's line for seizing said repeater, means responsive to the seizure of said repeater for selecting said toll trunk line and for signalling an operator at the toll exchange, means controlled over said toll trunk line and said repeater by the operator for extending the connection from said calling line to either a local or a distant called subscriber's line, and operator controlled means for freeing said toll trunk line leaving the connection through said repeater established between said calling and called lines.
6. In a telephone system, a local exchange, a distant exchange, and a toll exchange, local subscribers' lines terminating in the local exchange and distant subscribers' lines terminating in the distant exchange, a dial-back repeater in the local exchange, a toll trunk line extending to the toll exchange accessible to said repeater, means responsive to a call by a local calling subscriber's line for seizing said repeater, means responsive to the seizure of said repeater for selecting said toll trunk line and for signalling an operator at the toll exchange, trunk lines connecting the distant and local exchanges, means controlled over said toll trunk line and said repeater by the operator for selecting one of the trunk lines connecting the local and distant exchanges and for thereafter extending the connection from the calling line by way of said repeater and said last trunk line to a distant called subscriber's line, and operator controlled means for freeing the toll trunk leaving the connection through said repeater and trunk line established between the local and distant subscribers' lines.
7. In a telephone system, means including a calling line, a called line, and an operator's trunk line for establishing a Y talking connection, a trunk reversing relay for reversing battery back over the operator's trunk line, means for operating said relay in response to said calling line extending said connection to said operator's trunk line, means for deenergizing said relay in response to the operator further extending said connection toward the called line, and means for again energizing said relay when the called party answers.
8. In a telephone system, means including a calling line, a called line, and an operator's trunk line for establishing a Y talking connection, a trunk reversing relay for reversing battery back over said trunk line, a line reversing relay for reversing battery back to the calling line, means for operating said trunk reversing relay in response to said calling line extending a connection to said trunk line, means for operating said line reversing relay in response to the operator answering, means for deenergizing said trunk reversing relay in response to the operator extending said connection to the called line, a relay operated in response to the called party answering for again operating said trunk reversing relay and for maintaining said line reversing relay in operated position, and means for freeing said trunk line for use on other calls while maintaining the connection between the calling and called lines.
9. In a telephone system, a two-way trunk line, an outgoing repeater and an incoming switch associated with said trunk line, a battery revers-

ing relay for reversing battery back toward a calling line, means for seizing said repeater and trunk line on an outgoing call, means for operating said switch on an incoming call over said 5 trunk line, means for operating said relay in response to the outgoing call being answered, means for operating said relay in response to the operation of said switch on an incoming call, and contacts closed by the operation of said relay for 10 guarding said repeater from seizure.

10. In a telephone system wherein subscribers' lines in two automatic exchanges connected by trunk lines complete local automatic connections in their respective exchanges but are restricted 15 from completing inter-exchange calls over said trunk lines to called subscribers' lines in the far exchange, a toll trunk line comprising two talking conductors connecting one of the exchanges with an operator's position at a toll exchange, 20 means including a dial-back repeater in one of the exchanges for seizing the toll trunk line and for signalling the operator thereover in response to a call by a subscriber in either automatic exchange initiating an inter-exchange call, a dial- 25 back lineswitch individual to said repeater, local selectors accessible to said lineswitch, a relay in said repeater, means controlled over the two talking conductors of said toll trunk line in parallel for operating said relay, a circuit for operating 30 said lineswitch to select an idle local selector closed by the operation of said relay, and means controlled over the two talking conductors of said toll trunk line in series for operating said selector to further extend said inter-exchange call 35 toward completion.

11. In a telephone system wherein subscribers' lines in two automatic exchanges connected by trunk lines complete local automatic connections in their respective exchanges but are restricted from 40 completing inter-exchange calls over said trunk lines to called subscriber's lines in the far exchange, a toll trunk line comprising two talking conductors connecting one of the exchanges with an operator's position at a toll exchange, means 45 including a dial-back repeater in one of the exchanges for seizing said toll trunk line and for signalling the operator thereover in response to the initiation of an inter-exchange call from a subscriber's line in either automatic exchange, a 50 relay in said repeater, means controlled over the two talking conductors of said toll trunk line in parallel by the operator for operating said relay, a circuit for further extending the said inter-exchange call closed by the operation of said relay, means controlled over the two talking conductors of said toll trunk line in series by the operator for opening and closing said circuit, and 55 automatic switches controlled by the closing and opening of said circuit for completing the inter-exchange call to a called line.

12. In a telephone system wherein subscribers' lines in two automatic exchanges connected by trunk lines complete local automatic connections in their respective exchanges but are restricted 60 from completing inter-exchange calls over said trunk lines to called subscribers' lines in the far exchange, a toll trunk line comprising two talking conductors connecting one of the exchanges with an operator's position at a toll exchange, 65 means including a dial-back repeater in one of the exchanges for seizing said toll trunk line and for signalling the operator thereover in response to the initiation of an inter-exchange call from a subscriber's line in either automatic exchange, a 70 relay in said repeater, means controlled over the 75

two talking conductors of said toll trunk line in parallel by the operator for operating said relay, a circuit for further extending the said inter-exchange call closed by the operation of said relay, means controlled over the two talking conductors of said toll trunk line in series by the operator for opening and closing said circuit, automatic switches controlled by the closing and opening of said circuit for completing the inter-exchange call to a called line, and means for 10 freeing said toll trunk line for other uses while maintaining the inter-exchange connection between the calling and called lines.

13. In a telephone system wherein subscribers' lines in two automatic exchanges connected by 15 trunk lines complete local automatic connections in their respective exchanges but are restricted from completing inter-exchange calls over said trunk lines to called subscribers' lines in the far exchange, a toll trunk line comprising two talking 20 conductors connecting one of the exchanges with an operator's position at a toll exchange, means including a dial-back repeater in one of the exchanges for seizing said toll trunk line and for signalling the operator thereover in response to the initiation of an inter-exchange call from a subscriber's line in either automatic exchange, a 25 relay in said repeater, means controlled over the two talking conductors of said toll trunk line in parallel by the operator for operating said relay, a circuit for further extending the said inter-exchange call closed by the operation of said relay, means controlled over the two talking conductors of said toll trunk line in series by the operator for opening and closing said 30 circuit, automatic switches controlled by the closing and opening of said circuit for completing the inter-exchange call to a called line, and means for removing said relay from the control of said 35 relay operating means in response to the subscriber on the called line answering.

14. In a telephone system wherein subscribers' lines in two automatic exchanges connected by trunk lines complete local automatic connections in their respective exchanges but are restricted from completing inter-exchange calls over said 45 trunk lines to called subscribers' lines in the far exchange, a toll trunk line comprising two talking conductors connecting one of the exchanges with an operator's position at a toll exchange, 50 means including a dial-back repeater in one of the exchanges for seizing said toll trunk line and for signalling the operator thereover in response to the initiation of an inter-exchange call from a subscriber's line in either automatic exchange, a 55 relay in said repeater, means controlled over the two talking conductors of said toll trunk line in parallel by the operator for operating said relay, a circuit for further extending the said inter-exchange call closed by the operation of said 60 relay, means controlled over the two talking conductors of said toll trunk line in series by the operator for opening and closing said circuit, automatic switches controlled by the closing and opening of said circuit for completing the inter-exchange call to a called line, said relay operating means controlled by the operator over the two talking conductors of said toll trunk line in parallel to release and reoperate said relay in case of failure to complete the connection to the 65 called line, the release of said relay opening said circuit to release said automatic switches and the reoperation of said relay again closing said circuit, and means for removing said relay from the control of said relay operating means in re- 70 75

- 5 response to the subscriber on the called line answering.
- 10 15. In a telephone system, an automatic exchange, a toll exchange, a toll trunk line connecting said exchanges, a repeater in the automatic exchange, a switching relay in said repeater for connecting ringing current to the conductors of said trunk line to signal an operator, for operatively connecting said repeater to the conductors of said trunk line, and for guarding said trunk line from seizure by other repeaters, means for seizing said repeater, and means for operating said relay only in case ringing current is available to signal the operator.
- 15 16. In a telephone system, outgoing trunk lines, outgoing repeaters terminating said outgoing repeaters terminating said outgoing trunk lines, selector switches having access to said trunk lines by way of said repeaters, a test conductor individual to each repeater normally having one pole of battery connected thereto for indicating the idle condition of said repeater and trunk line, means for operating one of said selectors to connect with the first idle repeater having said one pole of battery connected to its test conductor, a first slow relay in said repeater operated in response to said connection for disconnecting said one pole of battery from said test conductor and for connecting the opposite pole of battery therefrom to busy said repeater and trunk line to the other selectors, a second slow relay in said repeater directly controlled and operated by said first relay, means for releasing the connection between said selector and said repeater and for releasing said first and second relays in succession, and a circuit controlled by said second relay for delaying the application of said one pole of battery to the test conductor of said repeater until said second relay is fully restored.
- 20 25 30 35 40 45 17. In a telephone system, an outgoing trunk line, a repeater terminating said trunk line, a test conductor in said repeater, a first slow relay in said repeater controlled by said first relay, a battery reversing relay in said repeater, a circuit including normally closed contacts on said battery reversing relay and back contacts on said first

and second relays in series for connecting one pole of battery to said test conductor to indicate the idle condition of said repeater and trunk line, and front contacts on each of said relays for connecting the opposite pole of battery to said test conductor to busy said repeater and trunk line.

18. In a telephone system, an outgoing trunk line, a repeater individual thereto, a test conductor in said repeater, a first slow relay in said repeater, a second slow relay in said repeater controlled by said first relay, a circuit including back contacts on said first and second relays in series for connecting one pole of battery to said test conductor to indicate the idle condition of said repeater and trunk line, and front contacts on each of said relays for connecting the opposite pole of battery to said trunk line to busy said repeater and trunk line.

19. In a telephone system, a plurality of trunk lines, an all-relay monitor selector, a trunk connecting relay in said selector for each trunk line, means for seizing said selector and for directly operating said trunk connecting relays in succession to connect with successive ones of said trunk lines regardless of their idle or busy conditions, and means in said selector for reversing battery back over the path it was seized each time a connection is made with a busy one of said trunk lines to indicate such busy condition.

20. In a telephone system, a plurality of trunk lines, an all-relay monitor selector, a trunk connecting relay in said selector for each trunk line, means for seizing said selector and for directly operating said trunk connecting relays in succession to connect with successive ones of said trunk lines regardless of their idle or busy condition, means in said selector for reversing battery back over the path it was seized each time a connection is made with a busy one of said trunk lines to indicate such busy condition, and a talking circuit completed between said selector and each of said trunk lines in response to the operation of the corresponding trunk connecting relay.

NORMAN H. SAUNDERS.
